(57) **CLAIM**

The ornamental design for a housing with flange for electrical and mechanical components, as shown and described.

DESCRIPTION

FIG. 1 is a perspective view of a housing with flange for electrical and mechanical components showing the new design.

FIG. 2 is a top view of the housing with flange for electrical and mechanical components of FIG. 1.

FIG. 3 is a side view of the housing with flange for electrical and mechanical components of FIG. 1; and,

FIG. 4 is a bottom view of the housing with flange for electrical and mechanical components of FIG. 1.

The dashed lines in the drawings represent environmental structure that forms no part of the claimed design. The dash-dot-dash lines in the drawings represent boundaries that do not form part of the claimed design.
